UNITED STATES PATENT OFFICE.

ALLEN B. BOYER AND ORA DAVISSON, OF TREES, LOUISIANA.

BAILING APPARATUS.

1,383,069.

Specification of Letters Patent. Patented June 28, 1921.

Application filed April 24, 1920. Serial No. 376,363.

To all whom it may concern:

Be it known that we, ALLEN B. BOYER and ORA DAVISSON, citizens of the United States, residing at Trees, in the parish of Caddo and State of Louisiana, have invented certain new and useful Improvements in Bailing Apparatus, of which the following is a specification.

This invention relates to well drilling apparatus, and especially apparatus for deep wells, such as oil wells and the like, and has for an object to provide actuating mechanism for the bailer cables, whereby the bailing reel is placed away from the derrick and with means at the derrick for controlling the reel, for winding, holding or liberating the bailer.

A further object of the invention is to provide a bailing reel with a constantly driven shaft with the reel drum rotatable thereon and means actuated from a position at the derrick for connecting the reel with the shaft at times, or applying a brake thereto at times, or with an intermediate step releasing the reel from both of said controls.

With these, and other objects in view, the device comprises certain novel elements, mechanical movements, parts and combinations as will be hereinafter more fully described and claimed.

In the drawings,

Figure 1 is a view in end elevation of the improved bailing reel, associated with conventional type of derrick and prime mover.

Fig. 2 is a view of the bailing reel in side elevation, as indicated by arrow 2 at Fig. 1.

Fig. 3 is a sectional view of the reel structure taken on line 3—3 of Fig. 2.

Fig. 4 is a fragmentary, detail, plan view of the mechanical movement for operating the clutch, taken on line 4—4 of Fig. 2.

Like characters of reference indicate corresponding parts throughout the several views.

The improved bailing reel structure, which forms the subject matter of this application, is adapted to be associated with any form of derrick, shown conventionally at 10, and operated from any type of prime mover, shown conventionally at 11, the latter driving the usual bull-wheel shown conventionally at 12. The power for driving the reel mechanism is taken from the shaft 13, which journals the bull-wheel 12, by means of sprocket 14 and sprocket chain 15.

The sprocket chain 15 engages sprocket 16 upon a shaft 17 journaled upon a frame 18. Upon the shaft 17 the reel is mounted to freely rotate, such reel comprising sleeve 60 19 and flanges 20 and 21. Upon this reel the bailing cable 22 is wound, passing up to and over a pulley at the top of the derrick and downwardly to the line in the usual well known manner.

The shaft 17, connected as it is with the bull-wheel 12, is constantly driven, provision therefore must be made for winding the cable upon the reel, when it is desirable so to do for retarding the reel or holding it against movement when either of said conditions are desirable, or for loosing the reel, to permit the bailing apparatus to drop when that is found necessary. The means for positively rotating the reel, for winding the cable, comprises a drum 23 associated with an internal expanding clutch 24 of the usual and ordinary type. This clutch is actuated by a lever 25 which in turn connects at its lower end with a bell-crank lever 26 pivoted to the frame 18 at 27. The bell-crank lever 26 is also pivoted to the thrust-bar 28 which extends from the frame, adjacent to the surface of the ground, to the derrick 10 and connects with any usual and ordinary type of manual control, shown conventionally as the lever 29.

As shown in the drawings the parts are set to clamp the clutch 24 within the drum 23. The movement of the lever 29, from the position shown at Fig. 1 to move the thrust bar, in the direction indicated by arrows at Figs. 1, 3 and 4, results in swinging the lever 25 also in the direction indicated by the arrow at Fig. 2. The movement of the lever 29 to the middle notch of the segment 30 releases the clutch permitting the reel to rotate freely upon the shaft 17 and the bailing cable to unwind. Any further movement of the thrust bar 28, manipulated by lever 29 causes lever 31 to continue movement, in

the direction indicated by the arrow upon said lever at Fig. 3, communicating such movement to the hand brake 32, whereby the hand brake is tightened upon the drum 23 to retard the reel or hold it stationary.

With the lever 29 swung to the limit of its movement opposite that shown at Fig. 1, the hand brake 32 is applied and the reel held rigid. It will be noted, therefore, that there are three steps in the control of the reel, one in which the clutch 25

connects the reel to rotate on the shaft 17; one in which the band brake 32 holds the reel stationary and the reel and cable at any point which has been reached, in the winding or unwinding, and an intermediate step when both the clutch and the brake are released, leaving the reel free to rotate under the weight of the bailing apparatus.

Having thus fully described our said invention what we claim as new and desire to secure by Letters Patent, is:

The combination with a well rig including a derrick and a prime mover, of a bailing apparatus comprising a shaft constantly driven from the prime mover, a reel loose on the shaft, a clutch for connecting the reel to the shaft, a lever for operating the

clutch, a brake to hold the wheel against rotation, a lever for operating the brake, a manually operated lever at the derrick, a rod extending therefrom attached to the brake lever, a bell crank lever having one arm attached to the rod and the other arm attached to the clutch lever, substantially as set forth.

In witness whereof, we have hereunto set our hands and seals at Shreveport, Louisiana, this 29th day of March, A. D. nineteen hundred and twenty.

ALLEN B. BOYER. [L. S.]
ORA DAVISSON. [L. S.]
